DIHYDROIMIDAZOLIUM COMPOUNDS

Horace A. Shonle, Indianapolis, and Edwin R. Shepard, Beech Grove, Ind., assignors to Eli Lilly and Company, Indianapolis, Ind., a corporation of Indiana

No Drawing. Application July 19, 1946,
Serial No. 684,778

6 Claims. (Cl. 260—309.6)

1

This invention relates to a group of new organic compounds and more particularly to new substituted dihydroimidazolium compounds. This application is a continuation-in-part of our prior application Serial No. 605,191, filed July 14, 1945, now abandoned.

Our new substituted dihydroimidazolium compounds have surface tension depressing and bacteriostatic properties, and have therapeutic value for combating various bacterial invasions.

By this invention we have provided new compositions of matter which may be represented by the following formula:

wherein R and R₂ are the same or different aliphatic hydrocarbon radicals each having from 1 to 7 carbon atoms; R₁ is an aliphatic hydrocarbon residue having an average carbon content of 7 to 12 carbon atoms, the total number of carbon atoms in R₁ and the larger of R and R₂ being from 10 to 16, and the total number of carbon atoms in R, R₁, and R₂ being not greater than 17; X is an anion; and n is an integer from 1 to 3 inclusive.

The R₁ substituent has an average carbon content of 7 to 12 carbon atoms. By this we mean that the final composition is either one consisting of a single compound in which the R₁ substituent is a radical having a single definite number of carbon atoms, i. e., nonyl, undecyl, etc., or one consisting mainly of such a specific compound mixed with lesser amounts of corresponding compounds in which respectively the R₁ substituents are close homologues of the single definite radical of that specific compound, the mixture being of such proportions that the average R₁ carbon content is within the range of from about 7 to about 12. When the R₁ substituent is derived from a pure compound, it will normally consist of a single specific radical. But it may be derived from a commercial product, as obtained by distillation or rectification, which consists mainly of a compound having a definite number of carbon atoms, but which may also contain close homologues of such compound, in which case the R₁ substituent will comprise radicals of corresponding variation. For example, the R₁ substituent may be derived from commercial lauric acid, consisting mainly of lauric acid itself, with 12 carbon atoms, but also including alkyl acids of 10 and 14 carbon atoms, in

2

which case the R₁ substituent in the resulting product will be mainly the 11-carbon undecyl radical but will include some homologues such as the 9-carbon and 13-carbon radicals. The R and R₂ substituents may also contain such variations, but in most cases substantially pure starting compounds will be convenient for these substituents, so that they may consist of definite radicals.

The compositions of matter of our invention may be regarded as comprising positively charged dihydroimidazolium cations which are substituted by aliphatic hydrocarbon radicals and which are combined with negatively charged anions. The aliphatic hydrocarbon groups may be selected from straight chain saturated, branched chain saturated, and straight and branched chain unsaturated groups. The negatively charged anion associated with the dihydroimidazolium cation may be any one of a number of negative ions such as, for example, the chloride, bromide, sulfate, acetate, or phosphate ions. By way of example, and referring to the above structural formula, when R is a methyl group, R₁ a decyl group, R₂ a methyl group, X a chloride ion, and n is 1, the compound is 1,3-dimethyl-2-decyl-4,5-dihydroimidazolium chloride.

In compounds of this invention the sum of the carbon atoms contained in the R₁ group and the larger of the R and R₂ groups ranges from 10 to 16 carbon atoms, and the sum of the carbon atoms in the three groups R, R₁, and R₂ does not exceed 17. The following examples illustrate these limitations: When R and R₂ each contain 1 carbon atom, R₁ must contain at least 9 carbon atoms, but may contain any number up to its own limit of 12 carbon atoms; when R contains 6 carbon atoms and R₂ contains 1 carbon atom, R₁ must contain at least its own minimum of 7 carbon atoms but may not have more than 10 carbon atoms; and when R₁ contains 11 carbon atoms, neither R nor R₂ may contain more than 5 carbon atoms and together they may contain not more than 6 carbon atoms.

It should be noted that two isomeric forms of our compounds exist simultaneously because of a dynamic equilibrium. Thus, compounds of our invention may be represented by either of the following formulae:

Formula A

Formula B

wherein R, R₁, R₂, X and n have the same significance as before. In Formula A, the nitrogen at position 1 is tertiary, and the nitrogen at position 3 is quaternary. In Formula B, the nitrogen at position 1 is quaternary, and the nitrogen in position 3 is tertiary. In the specification and claims we employ for convenience Formula A, wherein R is attached to the tertiary nitrogen at position 1, and R₂ is attached to the quaternary at position 3. It will be understood that the two forms illustrated are to be regarded as equivalent and that both forms are to be considered as within the scope of this invention.

The compounds of this invention are distinguished by their effective bacteriostatic properties and their low hemolytic effect. Corresponding compounds in which the substituent in the R₁ position has less than 7 carbon atoms have ineffective antibacterial action, and when the R, R₁, and R₂ substituents exceed the limits set forth in number of carbon atoms, the compounds have a large hemolytic effect and are correspondingly toxic.

In preparing the compounds of our invention, we may start with a dihydroimidazole containing the desired R₁ substituent and one or the other of the R and R₂ substituents. Such starting compound may be obtained from a dihydroimidazole containing the R₁ substituent by reaction with an alkylating agent, to add the R or R₂ substituent. Broadly, we may prepare the compounds embodying our invention by reacting such a starting compound with an alkylating agent such as, for example, the nitrates, sulfates, or halides of aliphatic hydrocarbons, to cause the addition of the remaining R or R₂ substituent and to supply the anion X in the foregoing formulas. Preferably, and because of their ready availability, we employ the halides—by which we mean the chlorides, bromides, and iodides, and exclude the fluorides—and thus preferably form compounds in which the anion X is a halogen anion—by which we mean a chloride, bromide, or iodide anion. The reaction is effected by mixing the substituted dihydroimidazole with the halide of the aliphatic hydrocarbon, allowing any spontaneous reaction to subside and subsequently heating the mixture to complete the reaction. The product may be purified by recrystallization or precipitation from suitable solvents or mixtures thereof. The theoretical amount of the aliphatic hydrocarbon halide may be used but it is preferable to use an excess to assure completion of the reaction. The reaction is conveniently, although not necessarily, carried out in a closed system thus eliminating any loss of the aliphatic hydrocarbon halide by volatilization. If desired, a suitable nonreactive solvent such as, for example, alcohol or ethyl acetate may be used as a vehicle during the reaction.

In preparing the compounds of our invention there may be used as starting material a mixture of similarly substituted dihydroimidazoles. Thus for example, the starting material may be a group of dihydroimidazoles wherein (referring to the above formulas) R₁ is a mixture of aliphatic hydrocarbon radicals having an average of about 11 carbon atoms and consisting mainly of undecyl, but containing some higher and lower homologues in the range of about 9 to 15 carbon atoms (as derived, for example, from commercial lauric acid). Such starting material may be reacted with a halide of an aliphatic hydrocarbon such as methyl chloride to yield a mixture of the correspondingly substituted dihydroimidazolium

chlorides, consisting mainly of the compound in which the R₁ substituent is undecyl and including in minor amounts compounds in which the R₁ substituents are adjacent homologues of the undecyl radical.

It should be noted that the compounds of our invention comprising both of two isomeric forms as mentioned heretofore may be prepared by either of two routes. A dihydroimidazole substituted by the groups R and R₁ may be alkylated with an R₂-containing alkylating agent. Likewise a dihydroimidazole substituted by the groups R₁ and R₂ may be alkylated by an R-containing alkylating agent. The same compound or mixture of compounds results when R, R₁, and R₂ are correspondingly identical in each alkylation reaction.

The compounds of our invention are salt-like and generally water-soluble, and consequently are subject to many of the ionic reactions which typify soluble inorganic salts. By anionic interchange reactions, one anion may be substituted for another. For example, by taking advantage of the lower solubility of a substituted dihydroimidazolium sulfate as compared with the solubility of the corresponding imidazolium chloride, the sulfate may be crystallized preferentially from a solution containing the dihydroimidazolium, sulfate and chloride ions. Illustrating another method of effecting this conversion, an aqueous solution of substituted dihydroimidazolium halide may be shaken with substantially insoluble silver sulfate, whereby the halide ion is removed as insoluble silver halide leaving in solution the dihydroimidazolium sulfate. Additionally, ionic interchange may be effected through the hydroxyl ion as an intermediate. Upon shaking an aqueous solution of a substituted dihydroimidazolium halide with silver oxide, there is formed the corresponding soluble dihydroimidazolium hydroxide and insoluble silver halide. Treatment of the soluble dihydroimidazolium hydroxide solution with the appropriate acid forms the desired dihydroimidazolium compound.

45 The following examples illustrate our invention:

Example 1

1,3-dimethyl-2-n-undecyl-4,5-dihydroimidazolium iodide represented by the formula

50 may be prepared by reacting 1-methyl-2-n-undecyl-4,5-dihydroimidazole with methyl iodide in the following manner:

60 The 1-methyl-2-n-undecyl-4,5-dihydroimidazole used in the synthesis was prepared by refluxing a mixture of 171 g. of ethyl laurate and 135 g. of anhydrous ethylene diamine at 110–112° C. for 12 hours. The alcohol and excess ethylene diamine were removed by distillation and 172 g. of crude N-lauroyl ethylene diamine were obtained. A mixture of 162 g. of the crude N-lauroyl ethylene diamine and 187 g. of powdered calcium oxide was heated with stirring at 225° C. for 36 hours. The reaction mixture was cooled to room temperature and extracted three times with about 350 cc. of alcohol. The extract was distilled in vacuo and the reaction product, 2-n-undecyl-4,5-dihydroimidazole, distilled at 180–75 189° C./10 mm. It melted at 81–83° C. To 56.5 g.

5

of the 2-n-undecyl-4,5-dihydroimidazole were added 31.7 g. of dimethyl sulfate, the temperature of the reaction during the addition being maintained at about 85° C. About 150 cc. of water were added and the reaction mixture stirred until the solid material had dissolved. An aqueous solution of 20 g. of 50 percent sodium hydroxide and about 150 cc. of butyl alcohol was added to the reaction mixture with agitation, the mixture filtered and the butyl alcohol layer separated. The reaction product, 1-methyl-2-n-undecyl-4,5-dihydroimidazole, was obtained by evaporation of the butyl alcohol and distillation of the residue at 167-172° C./6 mm.

A cold mixture of 1.8 g. of 1-methyl-2-n-undecyl-4,5-dihydroimidazole and 1.7 g. of methyl iodide was sealed in a tube. When the tube and its contents were warmed to about room temperature, a spontaneous reaction took place after which reaction the tube was heated for one hour at 100-110° C. The tube was then cooled to about room temperature and its contents dissolved in about 50 cc. of hot ethyl acetate. The hot solution was treated with decolorizing carbon, filtered and the filtrate cooled to about 0° C., whereupon crystals of 1,3-dimethyl-2-n-undecyl-4,5-dihydroimidazolium iodide separated. These were filtered off and redissolved in hot ethyl acetate from which solution, upon cooling to about 0° C., there separated substantially pure 1,3-dimethyl-2-n-undecyl-4,5-dihydroimidazolium iodide which melted at about 120-122° C.

Example 2

1-n-amyl-2-n-undecyl-3-methyl- 4,5 - dihydro-imidazolium iodide represented by the formula

may be prepared by reacting 1-n-amyl-2-n-undecyl-4,5-dihydroimidazole with methyl iodide 4 as follows:

The 1-n-amyl-2-n-undecyl-4,5-dihydroimidazole used in the synthesis was prepared by treating the 2-n-undecyl-4,5-dihydroimidazole described in Example 1 with n-amyl chloride in the following manner: To 84.9 g. of 2-n-undecyl-4,5-dihydroimidazole heated to 140-150° C. were added dropwise 21.7 g. of n-amyl chloride. The temperature of the reaction mixture was held at 147-154° C. for a total of 16 hours. The reaction mixture was cooled to about 60° C. and a solution of 17.1 g. of 50 percent sodium hydroxide in a mixture of about 150 cc. of water and 150 cc. of butyl alcohol was added to the reaction mixture with agitation and the agitation continued for one hour. The butyl alcohol layer was then separated and distilled to remove the butyl alcohol and water and the residue distilled at 145-180° C./5 mm. 55 60

A cold mixture of 1.5 g. of 1-n-amy1-2-n-un-decyl-4,5-dihydroimidazole and 1.7 g. of methyl iodide was sealed in a tube. Upon warming to about room temperature, the contents of the tube reacted spontaneously, after which reaction the tube was heated to 110° C. for one hour. The tube was then cooled to about room temperature, its contents dissolved in about 40 cc. of hot ethyl acetate and the hot solution treated with decolorizing carbon and filtered. No precipitate was obtained upon cooling the filtrate to about 0° C. The fil- 7

1

trate was thereupon treated with an excess of petroleum ether which precipitated as an oil the 1-n-amyl-2-n-undecyl-3-methyl-4,5-dihydroimidazolium iodide. The oil was purified by dissolving it in hot ethyl acetate, treating with de-colorizing carbon, filtering and adding an excess of petroleum ether to reprecipitate the 1-n-amyl-2-n-undecyl-3-methyl-4,5-dihydroimidazolium iodide as an oil which was dried in a vacuum desiccator over sulfuric acid.

Example 3

1,3-dimethyl-2-n- nonyl - 4,5 - dihydroimidazo-
lium iodide represented by the formula

may be prepared by reacting 1-methyl-2-n-nonyl-4,5-dihydroimidazole with methyl iodide as follows:

25 1-methyl-2-n-nonyl-4,5-dihydroimidazole was prepared from anhydrous ethylene diamine and ethyl decanoate in substantially the same manner as was prepared 1-methyl-2-n-undecyl-4,5-dihydroimidazole described in Example 1.

30 A cold mixture of 1.5 g. of 1-methyl-2-n-nonyl-
4,5-dihydroimidazole and 1.7 g. of methyl iodide
was sealed in a tube. Upon warming to about
room temperature the contents of the tube re-
acted spontaneously after which reaction the
5 tube was heated to 110° C. for one hour. The
tube was then cooled to about room temperature,
its contents dissolved in about 50 cc. of a hot
mixture of ethyl acetate and ethyl alcohol, and
the solution treated with decolorizing carbon and
0 filtered. Upon cooling the filtrate to about 0° C.,
there separated a crystalline precipitate of 1,3-
dimethyl-2-n-nonyl-4,5-dihydroimidazolium io-
dide which after recrystallization from ethyl
acetate melted at about 50-51° C.

Example 4

1-methyl-2-n-nonyl-3-methallyl-4,5-dihydroimidazolium chloride represented by the formula

may be prepared from 1-methyl-2-n-nonyl-4,5-dihydroimidazole and methallyl chloride as follows:

30 A cold mixture of 1.3 g. of 1-methyl-2-n-nonyl-
4,5-dihydroimidazole and 1.7 g. of methallyl chloride was sealed in a tube. The mixture upon warming to about room temperature reacted spontaneously after which reaction the tube was
35 heated to 100-110° C. for one hour. The tube was then cooled to about room temperature, its contents dissolved in about 50 cc. of boiling ethyl acetate, and the solution treated with decolorizing carbon and filtered. Upon cooling the filtrate to
40 about 0° C., no precipitate was obtained. The filtrate was thereupon treated with an excess of petroleum ether which precipitated as an oil the 1-methyl-2-n-nonyl-3 - methallyl-4,5 - dihydroimidazolium chloride. The oil was purified by
45 dissolving it in hot ethyl acetate, treating with de-

7

colorizing carbon, filtering, and adding an excess of petroleum ether to reprecipitate the 1-methyl-2-n-nonyl-3-methallyl-4,5 - dihydroimidazolium chloride as an oil which was then dried in a vacuum desiccator over sulfuric acid.

Example 5

A mixture of substituted dihydroimidazolium chlorides represented by the following formula:

wherein R_1 represents a mixture of aliphatic hydrocarbon radicals derived from commercial ethyl laurate may be prepared by the method of Example 1 except that in place of pure ethyl laurate as used in Example 1 there is used ethyl laurate obtained from commercial lauric acid, and in place of methyl iodide there is used methyl chloride.

We claim:

1. A composition of matter represented by the formula

in which R and R₂ are aliphatic hydrocarbon radicals each having from 1 to 7 carbon atoms, R₁ is an aliphatic hydrocarbon residue having an average carbon content of 7 to 12 carbon atoms, the sum of the number of carbon atoms in R₁ and the larger of R and R₂ being from 10 to 16, and the sum of the number of carbon atoms in R, R₁, and R₂ being not over 17; X is an anion; and n is an integer from 1 to 3 inclusive.

2. A composition of matter represented by the formula

in which R and R_2 are aliphatic hydrocarbon radicals each having from 1 to 7 carbon atoms and one of which is saturated, R_1 is an aliphatic hydrocarbon residue having an average carbon content of 7 to 12 carbon atoms, the sum of the number of carbon atoms in R_1 and the larger of R and R_2 being from 10 to 16, and the sum of the number of carbon atoms in R , R_1 , and R_2 being not over 17; X is an anion; and n is an integer from 1 to 3 inclusive.

8

3. A composition of matter represented by the formula

in which R and R_2 are aliphatic hydrocarbon radicals each having from 1 to 7 carbon atoms, 10 R_1 is an aliphatic hydrocarbon residue having an average carbon content of about 11 carbon atoms and consisting mainly of 11-carbon radicals, the sum of the number of carbon atoms in R , R_1 , and 15 R_2 being not over 17; X is an anion; and n is an integer from 1 to 3 inclusive.

4. A composition of matter represented by the formula

25 wherein R₁ is an aliphatic hydrocarbon residue derived from commercial lauric acid and having an average carbon content of 11 carbon atoms, and H₂A is a halogen anion other than fluorine.

5. 1,3-dimethyl-2-n-undecyl-4,5 - dihydroimidazolium iodide represented by the formula

6. 1,3-dimethyl-2-n-nonyl - 4,5 - dihydroimidazolium iodide represented by the formula
